(57) CLAIM

The ornamental design for a chopping board, as shown and described.

DESCRIPTION

FIG. 1 is a top plan view of a chopping board having an extendable tray according to the design, with the extendable tray being shown in its retracted position;

FIG. 2 is a bottom plan view of a chopping board of FIG. 1;
FIG. 3 is a front elevational view of the chopping board of FIG. 1;

FIG. 4 is a side elevational view of one side of the chopping board of FIG. 1, with the extendable tray being shown in its retracted position, (the other side corresponds to the side);
FIG. 5 is a top plan view of the chopping board of FIG. 1, with the extendable tray being shown in an extended position; and,

FIG. 6 is a side elevational view of one side of the chopping board of FIG. 1, with the extendable tray being shown in an extended position, (the other side corresponds to this side).
